DAVID J. CONANT, OF MEMPHIS, TENNESSEE

WELL REAMER

Application filed January 2, 1932. Serial No. 584,383.

This invention relates to improvements in tools for drilling wells and more particularly to reamers for use in connection therewith for the purpose of locally enlarging the 5 well bore at a desired place or places.

Artesian wells particularly for water supply are drilled through varied strata and into water bearing sand. A well casing is provided which extends through these varied 10 strata and a strainer is secured to and projects below the lower end of the casing deep into if not entirely through the sand strata. Water must flow through this strainer from the sand and the openings in the strainer must 15 be large enough to allow the water flow, yet fine enough to restrain the sand. Even so the openings are rapidly enlarged and the strainer must eventually be replaced or the well be abandoned.

As one way of overcoming these difficulties 20 a bore much larger than the strainer used has been made and the space around the strainer has been filled with gravel. In such case reliance is placed on the gravel to restrain the 25 sand and the openings in the strainer need only be small enough to prevent the gravel entering. Such gravel type of wells have not only largely increased the strainer life but have also effected tremendous increases in 30 well capacity, but it has been necessary to make, at large extra cost, and ordinarily to completely case at still greater cost, a bore from the surface of the ground downward which approximated the desired diameter of 35 the gravel section except that some enlargement in the sand has been accomplished by washing the sand walls down. Unfortunately however, even then the resulting bore in the sand is uneven and cannot be satisfactorily controlled. It is the purpose of the 40 present tool to cut, and control the size of, this larger bore thereby permitting the bore and casing through the overlying strata to be only sufficiently larger than the strainer 45 and strainer pipe to be used to allow feeding in, or placing, of the gravel around the strainer after the strainer is in place.

The objects of the invention are to provide 50 a cutting tool for well drilling that may be passed down through the well bore or casing

and expanded at any desired point to cut a larger diameter hole therebelow.

A further object is to provide a tool of this character in which the reaming blades may be retracted without withdrawing the tool within 55 a casing and which tool may then be used for additional drilling at a smaller size and may again be enlarged at a lower depth to ream out an additional enlarged chamber or chambers without the necessity of following 60 same up with a casing.

A further object of the invention is to provide fluid pressure means for opening up the blades of the reamer in such a device and means for holding the blades in opened position, and a still further object is to deliver 65 water from the drill pipe past the reamer bit to the well drilling bit therebelow.

The means by which the foregoing and other objects are accomplished and the manner of their accomplishment will readily be understood from the following specification on reference to the accompanying drawings in which:—

Fig. 1 is a vertical section on the center line 75 of the drill stem and the reamer bits showing the bits in closed position;

Fig. 2 is a section at right angles to Fig. 1, showing the bits in fully extended position;

Figs. 3, 4 and 5 are respectively transverse 80 sections taken on the lines III—III; IV—IV and V—V of Fig. 1;

Fig. 6 is a fragmentary sectional elevation showing a modified form of port;

Fig. 7 is a side elevation corresponding 85 with Fig. 2; and

Fig. 8, an elevation corresponding with Fig. 1.

Referring now to the drawings in which the various parts are indicated by numerals, 90 10 is the casing of a well, 11 is the well bore through clay or other overlying strata and 12 an enlarged chamber being reamed out in the sand.

The tool comprising essentially a head 14 95 which is screwed on to a drill pipe 15 which extends to the surface of the ground. The head 14 is transversely slotted at 16 to provide a pocket in which reamer blades 17 may be housed. In such retracted position the 100

blades occupy the position 17A. Adjacent the upper end of the pocket is a pin 18 on which the blades 17 are pivoted, the holes for the pivot pin in the two blades being adjacent an end of each blade. Extending upward from the slot 16 is a restricted bore 19 in which is slidably mounted a closely fitting piston rod 20. Above the restricted bore 19 the head is provided with an enlarged 10 cylindrical bore or cylinder 21 in which is slidably disposed a piston 22 having suitable packing 23. Disposed beneath the piston 22 and abutting against the bottom 24 of the cylinder is a compression spring 25 which 15 acts to hold the piston and piston rod attached thereto in raised position. Adjacent the lower end of the cylinder is a port 26 which establishes free communication between the interior of the cylinder and the 20 surrounding well bore or casing. Adjacent the lower end of the piston rod 20 is a port 27 to which a passageway 28 leads from the top of the piston. The bore 19 for the piston rod is also provided with a port 29, this port 25 and the piston rod port 27 being out of register when the piston and rod are in raised position, but are brought into register when the piston and rod are fully depressed. The port 29 may discharge directly outward 30 through the head but preferably is connected by a pipe 30 with a reentrant port 31 establishing a passageway from the port 29 into the lower end of the head.

32 is a drill bit which may be secured directly into the lower end of the head. Preferably however a tubular drill bar 33 is secured into the head and the drill bit 32 secured to the lower end of such bar. The length of the bar is adjusted to various conditions of drilling met with. The drill bit 32 is provided with ports 34 which lead from a passageway 35 extending from the top of the bit. The port 29 is thus brought into communication through the channelway 30, the port 31, the tubular bar 33, and the passageway 35 with the ports 34, so that water forced downward through the drill stem is discharged in proximity to the cutting edge of the bit 32 and well below the reamer 40 blades 17. The piston rod 20 is also provided with a transverse notch or pocket 36 which is moved into register with a latch member when the piston 22 is fully depressed. This latch member may comprise a ball 37, which is inwardly urged by a compression spring 38. The spring 38 is held in place by a threaded plug 39. The restraining action of this latch on the piston rod is made less than the thrust of the spring 25, so that 50 the latter will definitely disengage the latch and force the piston upward.

Pivots connected to the blades 17, as by pins 40 are links 41 one link being connected to each of the blades. The opposite 65 ends of these links are both connected by a

joint pin 42 to the lower end of the piston rod 20, the relation of the linkage, the piston rod and the reamer blades being such that when the piston is in raised position the reamer blades are retracted into the closed position 17A, in the head 14, and when the piston is fully depressed the reamer blades are extended at right angles to the head. 70

In Fig. 6, a modification is shown in which the drill pipe is maintained in uninterrupted 75 communication with the drill bit through a passageway 29A, which connects the ports 27 and 29.

In using the device the well is ordinarily 80 bored through the underlying strata to the surface or slightly into the water bearing sands and ordinarily cased to such level. The drilling tools are then removed and the reamer head with the pilot drill is attached and lowered into the well. During such 85 lowering the reamer blades are held housed within the head, by the action of the spring 25 against the underside of the piston. When the head has been lowered to desired 90 position the drill stem and if necessary the surrounding well bore, are filled with water, the bore however ordinarily being full of water from prior operation or ground conditions. At such time fluid pressure on 95 the piston is balanced.

Rotation of the drill pipe and tools attached thereto is begun, and additional pressure is put on the column of water in the drill pipe to overcome the spring pressure, 100 force the piston downward and swing the reamer blades outward into cutting position, the full amount of such pressure being effective on the piston. As the piston reaches the end of this movement the blades extend 105 outward at right angles to the head, the ports 27 and 29 come into register and the pressure is reduced by escape of the water through the piston rod and these ports. At the same time however the latch 37 engages 110 the notch 36 establishing a resistance against return movement to compensate for such reduction in pressure. It will be understood that the cutting resistance exerted on the lower edge of the outer ends of the blades would in such instance also assist in holding 115 the blades in extended position and would assist in completing the downward movement of the piston and rod and the accomplishment of the locking action. Thereafter drilling with the blades in extended or reaming position is continued to such depth in the sand as is desired, an enlarged bore of uniform diameter being cut by reason of the rigidity of the structure. Water 120 discharged through the piston rod and ports during this operation flows upward carrying with it the cuttings of the reamer. At the same time the pilot drill is boring in advance of the reamer and establishing a bore to steady and center the reamer action. 125 130

In cutting through the sand it sometimes happens that an intermediate stratum is encountered such for instance as an indurated layer of sand approximating sandstone in 5 hardness which it is undesirable to ream through. In such case the pressure on the column of water in the drill tube is reduced. The drill tube is raised to free the reamer blades from the bottom of the cut and the 10 spring beneath the piston is allowed to overcome the resistance of the latch and close the blades within the head. The drill stem is again lowered and boring resumed with the pilot bit, but without water being supplied 15 through the drill stem, though should the modified form of passageway 29A be used, water under pressure insufficient to compress the spring, may be supplied for such drilling. After the stratum has been passed 20 through and desirable sand is again encountered water pressure is again established, or raised, on the piston and the reaming cycle above described is reestablished.

Having described my invention, what I 25 claim is:

1. In a well reamer a tubular drill stem, a slotted head carried thereby, a pair of reamer blades pivotally mounted in said slot, a cylinder chambered out in said head above 30 said slot and in communication with said stem, a restricted bore connecting said cylinder and slot, a piston within said cylinder, a compression spring within said cylinder acting to hold said piston in raised position, 35 a piston rod secured to said piston and extending downward therefrom, through said bore, links pivotally secured to said piston rod and to said blades, fluid pressure means for depressing said piston, means for reducing said 40 pressure on movement of said piston to depressed position, and means engaging said rod when fully depressed, to restrain return movement thereof.

2. In a well reamer a tubular drill stem, a 45 slotted head carried thereby, a pair of reamer blades pivotally mounted in said slot, a cylinder chambered out in said head above said slot and in communication with said stem, a piston within said cylinder, a compression 50 spring within said cylinder acting to hold said piston in raised position, means linking said piston to said blades, whereby depression of said piston will extend said blades and raising of said piston retract 55 them, fluid pressure means for depressing said piston, means for reducing said pressure on movement of said piston to depressed position, and means engaging with said linking means on full depression of said piston, 60 to restrain return movement thereof, said means being less powerful than said spring.

3. In a well reamer a tubular drill stem, a slotted head carried thereby, a pair of reamer blades pivotally mounted in said slot, a 65 cylinder chambered out in said head above

said slot and in communication with said stem, a restricted bore connecting said cylinder and slot, a piston within said cylinder, a compression spring within said cylinder acting to hold said piston in raised position, a 70 piston rod secured to said piston and extending downward therefrom, through said bore, links pivotally secured to said piston rod and to said blades, fluid pressure means for depressing said piston, means for reducing said 75 pressure on movement of said piston to depressed position, and co-timed means acting on said rod, to restrain return movement thereof.

4. In a well reamer a tubular drill stem, a slotted head carried thereby, a pair of reamer blades pivotally mounted in said slot, a cylinder chambered out in said head above said slot and in communication with said stem, a restricted bore connecting said cylinder and slot, a piston within said cylinder, a compression spring within said cylinder acting to hold said piston in raised position, a piston 80 rod secured to said piston and extending downward therefrom, through said bore, links pivotally secured to said piston rod and to said blades, fluid pressure means for depressing said piston, and means for engaging said piston rod in depressed position, to restrain return movement thereof, said means being 85 less powerful than said spring.

5. In a well reamer a tubular drill stem, a slotted head carried thereby, a pair of reamer blades pivotally mounted in said slot, said head being chambered to form a cylinder and a piston rod bore leading therefrom to said slot, said cylinder being in communication with said stem, a piston within said cylinder, and a piston rod in said bore, a compression spring within said cylinder acting to hold said piston in raised position, means linking said piston rod and to said blades, fluid pressure means for depressing said piston and extending said blades, and means acting on said rod in depressed position to resist return pressure thereof, said restraining means being less powerful than said spring.

6. In a well drilling tool, a tubular drill stem, a head secured on the lower end thereof and a drill bit carried by the lower end of said head, said bit having a downwardly extending tubular rod, closed at its lower end and laterally ported above said end, said head being chambered out to form a cylinder for said piston and guide bore for said rod, said cylinder being in communication with said stem, said guide bore being ported, and said rod and guide ports registering on depression of said piston, a passageway establishing communication between said guide port and said drill passageway, a compression spring within said cylinder normally holding said piston in raised position, and said ports out of communication; a pair of reamer blades pivotally mounted in said head, links connecting said 130

- piston rod to said reamer blades and effective to extend said blades on depression of said piston, said piston rod having a notch in a side thereof, and a spring urged plunger extending laterally inward through a wall of said head and engaging with said notch when said piston is fully depressed, the holding resistance of said plunger and notch being less powerful than said spring.
- 10 7. In a well reamer, a tubular drill stem, a head carried thereby, reamer blades pivotally mounted in said head, a piston having a downwardly extending tubular rod closed at its lower end, and laterally ported above said end, said head being chambered out to form a cylinder for said piston and guide bore for said rod, said cylinder being in communication with said stem, and said guide bore having a port, normally out of register with said rod port, said ports being registerable on depression of said piston, a compression spring within said cylinder normally holding said piston in raised position, and extending downward therefrom, links pivotally secured to said piston rod and to said reamer blades and effective to extend said blades on depression of said piston, a pilot bit disposed below said head and carried therefrom, said bit having ports therein and a passageway extending from said guide bore port to said bit ports, whereby communication is established between said drill stem and said bit ports when said blades are moved to reaming position.

35 In testimony whereof I hereunto affix my
signature.

DAVID J. CONANT.
